JEAN J. VANDERVEER, OF BRATTLEBORO, VERMONT.

PACKING-BOX.

1,186,624.

Specification of Letters Patent. Patented June 13, 1916.

Application filed February 17, 1915. Serial No. 8,767.

To all whom it may concern:

Be it known that I, JEAN J. VANDERVEER, a citizen of the United States, residing at Brattleboro, in the county of Windham and State of Vermont, have invented new and useful Improvements in Packing-Boxes, of which the following is a specification.

This invention relates to improvements in packing boxes, more particularly boxes for packing small articles such as artists' crayons, cigarettes and the like. It is customary to provide such boxes with a cover that is readily removable, to expose the top of a box body in which the contents are 10 closed between four walls. The user ordinarily wishes to select and remove only one of the articles contained, an operation which is more or less troublesome when the box is full, and particularly if, in the case of 15 crayons, he wants one of an under layer.

It is the object of the invention to provide so that in a box of that type, any part of either layer may be rendered easily accessible; so that the whole of both layers can be seen, 20 and the desired article selected individually without handling the others, and grasped by the fingers with ease. As this is accomplished by providing for lifting both layers so that their ends are exposed, to the general 25 object above stated are added the specific objects of so providing that individual articles in the layers are not disturbed by the operation of lifting and are not in danger 30 of falling out when lifted.

Further objects of the invention are to 35 provide a box which can be manufactured inexpensively, which can be sealed perfectly when closed, and which while utilizing a movable section of the exterior of the box 40 as a part of the structure, nevertheless does not require that such section be either large, or loose, or that it have any weakening effect on the general structure of the box.

It is also the object of the invention to 45 provide the other advantages that are incidental to the disclosure herein made, and it is intended by suitable expression in the appended claims to cover whatever features of patentable novelty exist in the invention 50 disclosed.

In the accompanying drawings which 55 illustrate an embodiment of the invention and suggest modifications thereof which may be made: Figure 1 is a front elevation; Fig. 2 is a side elevation in section on line 2-2 of Fig. 1; Fig. 3 is a side elevation of

a slightly different box, closed, in section on a plane corresponding to the line 2-2 of Fig. 1; Fig. 4 is a perspective of a modification showing the parts in a position corresponding to that of Fig. 2 with part broken away; and Figs. 5 and 6 are side elevations in section of modifications.

In the drawings a box is seen having a cover 10 which may be fastened by a paper hinge 11 to the box body, whose walls consist of a bottom 12 and four sides 13 capable of holding the contents when the cover is removed. Lying across the bottom of the box body, within it and under the contents thereof, is a stiff piece of cardboard, paper or other material comprising a thin supporting element extending across the bottom of the box which is herein referred to as a "slender beam" because it resembles a beam in its function of lifting or sustaining weight. Having only the thickness of paper or cardboard or the like, so that it adds practically nothing to the requisite depth of box for holding the regular contents, it is truly slender. At the same time it is of sufficient stiffness to lift the contents for the full width of the box when the beam itself is supported only in the middle. This ordinarily rests inactive in the bottom of the box, underlying the contents, but on occasions when it is desired to select and remove one of the articles, this beam lifts all of the articles to a position where they may be individually scanned and one of them selected 90 and taken with the fingers. The ends of this beam 14 are turned up as at 15, 15, at right angles into parallelism with each other, beside the sides 13 of the box. These upstanding parts are stiff and, when the beam is lying on the bottom, are flush with the sides of the box, not projecting above them nor noticeable to the eye. When the beam is lifted by any suitable means, as hereinafter explained, these stiff upright 95 sides rise with it and hold the articles from rolling off sidewise, which they would otherwise do when raised to the considerable degree which the invention makes possible.

The invention also provides means for 100 raising the beam 14 by simple pressure of the user's finger without disturbing the relation of the contained articles to each other as when pulled up by an underlying strap. As illustrated in Fig. 1 this means consists 110 in the provision of a movable part in what may be called the front exterior wall or side

of the box, *i. e.*, the vertical wall which is opposite the hinge. This movable part 16 is of cardboard like the wall of the box, and consequently is stiff; and it has a stiff extension inward along the bottom of the box marked 17. The beam 14 in this case consists merely of a piece of fairly stiff paper which is preferably attached by paste as at 18 to the middle or rear portion of the bottom of the box, on the interior, and which extends forward thence and is attached to the part 17. The parts 16 and 17 normally stand at right angles to each other and the top of the part 16 engages inside of the flange 10' of the cover when the cover is closed on the body of the box, as seen in Fig. 3. In Fig. 3 the part 17' may be considered to be an extension of the part 17 to the rear, and the part 14 a cross piece on top of it, with its ends 15 turned up, the part 17' (which is seen in longitudinal section in Fig. 3) being of the same width as parts 16 and 17 are seen to be in Fig. 1. Obviously, however, the part marked 17' in Fig. 3, might be of the full width of the box bottom, and be integral with the beam 14, in which case it would lose its distinctive numeral 17'. It is so represented in Figs. 1, 2 and 4 where the combined part has the numeral 14.

In operation one opens the box by removing the cover, whether it be attached or unattached to the body of the box, and then with his finger the user presses downward and outward on the top of the middle of the front wall of the box body. Being so pressed this movable part 16 swings outward and downward about the angle between the parts 16 and 17 as a pivot; and the part 17 simultaneously swings upward. In rising it lifts the broad sheet of paper herein designated the beam 14, flexing it or its support 17', if there be such separate part extending from front to back of the box. The beam is stiff in the lateral direction, a result which can be attained where the shape shown in Fig. 6 is used, by choosing paper that is stiff enough in the lateral direction and, if necessary, introducing a series of grooves 20 which break its stiffness in the direction from front to back. The attachment of the part 16 to the part 17, and of that in turn to the broad part 14, and of that in turn to the bottom 12 prevents the escape of this lifting means when the part 16 is pushed outward. In Fig. 1 the part 16 constitutes only a portion of the front wall of the box, and so the dislocation of these parts 16, 17, 14, is prevented by the fact that the part 14 is broader than the part 16 and therefore is held in by the remainder of the front wall whether it be pasted down to the bottom 12 or whether it be loose thereon; but in Fig. 4 a form is shown in which the part 16' corresponding to the part 16 constitutes the whole of the

front wall; and in that case the dislocation is prevented by the rear attachment of the paper beam 14 to the paper bottom 12. In either case it will be observed that the part 14 is an extra or additional piece not of itself forming part of the walls of the box body, but that it is attached to the part 16 or 16' which does actually constitute a part of the exterior walls of the box body; and that by mere pressure of the finger upon this part of the walls the contents of the box are lifted, without change in their existing relation to each other, to a place where the ends of both rows can be seen and any one of either row selected and removed easily by the fingers; and that while thus lifted out of the box body, and being handled, the articles are retained in their relations to each other by the upstanding stiff supplementary side walls 15.

In Figs. 5 and 6 a box is shown in which the part 16'' is a constituent part of the bottom 12. In this case the four side walls 13 of the box body are intact as is customary, but a portion of the bottom is cut out in any desired shape. For example, it may be circular. This portion 16'' is attached by paste represented at 19 to the stiff paper beam 14''. The beam is lifted by the user simply pressing his finger against the cut portion 16'' of the bottom. It should be noted in this construction that although a hole is cut through the bottom of the box the full width of contents are liftable, without the hole extending across the box; and that the hole is closed, so that no contents can be extracted through it from the package, by the inside paper which constitutes the stiff beam 14'', which extends across the box and covers area larger than the hole in the bottom that is made by the cutting of the part 16''; also that the contents are not accessible by pulling the part 16'' outward, because the part 14'' then acts as a bottom. When the box is filled, the contents keeps this paper 14'' pressed down tight on the bottom and keeps the part 16 pressed down into its place as a part of the bottom. The paper 14'' may either be pasted to the inside of the bottom as in the case of the paper 14 or it may be a simple card, lying loosely thereon and covering substantially the whole bottom, as the part 14'. In either case the box is safe against removal of contents through the opening in the bottom. In use such a package is handled by a very convenient motion, as the person who has removed the cover and holds the box in his left hand pushes with any finger on the particular part of the outside wall of the box, 16, 16' or 16'', which operates to lift the beam 14, 14' or 14''.

I claim as my invention:

1. A box for packing small articles, having a cover removable to expose the con-

- tents, combined with walls comprising a bottom and sides; a thin contents-supporting element within the box, extending across its bottom under said contents and liftable 5 from the bottom to raise the contents; an engagement between said element and a part of the exterior wall of the box; said part of the wall being movable with respect to the remainder of the wall, being not of 10 suitable position and extent to engage and lift all of the contents of the box and being adapted to lift said element when moved by pressure of the user's fingers.
2. A box for packing small articles, having a cover removable to expose the contents, combined with walls comprising a bottom and sides; a thin contents-supporting element within the box, extending across its bottom under said contents; means whereby 15 it may be lifted from the bottom by pressure, to raise the contents; and stiff upright pieces carried by the said element close to the box sides, forming retainers for the contents when lifted.
- 20 3. A box for packing small articles, having a cover removable to expose the contents, combined with walls comprising a bottom and sides; a thin contents-supporting element within the box, extending across its bottom under said contents and liftable from the bottom to raise the contents; an attachment between said element and a part of the exterior wall of the box; said part of the wall being movable with respect to the remainder of the wall, being not of suitable 25 position and extent to engage and lift all of the contents of the box and being adapted to lift said element when moved by pressure of the user's fingers and not being adapted 30 otherwise to lift all of the contents of the box; and means whereby said element holds in place said movable part of the wall, the whole being arranged and adapted for the said element to be lifted by the said movable 35 part when the latter is pressed by the user out of its ordinary position.
4. A box for packing small articles, having a cover removable to expose the contents, combined with walls comprising a bottom and sides; a thin contents-supporting element within the box, extending across its 40
- bottom under said contents and liftable from the bottom to raise the contents; there being a movable part of one of the box walls normally standing vertical; and another element connected therewith, normally lying horizontally on the bottom, these two being adapted to act jointly as a lever to lift said first mentioned element and the contents by downward and outward pressure on said 45 movable vertical part.
5. A box for packing small articles, having a cover removable to expose the contents, combined with walls comprising a bottom and sides; a thin contents-supporting element within the box, extending across its bottom under said contents and liftable from the bottom to raise the contents; there being a movable part of one of the box walls normally standing vertical; and another element connected therewith, normally lying 50 horizontally on the bottom, these two being adapted to act jointly as a lever to lift said first mentioned element and the contents by downward and outward pressure on said 55 movable vertical part.
6. A box for packing small articles, having a cover removable to expose the contents, combined with walls comprising a bottom and sides; a thin contents-supporting element within the box, extending across its bottom under said contents; one part of the 60 exterior wall of the box being movable with respect to the remainder of the wall and the whole being arranged and adapted for the said element to be lifted by the said movable part when the latter is pressed by the user 65 out of its ordinary position; said movable part extending only a fraction of the width of the box and said element extending across substantially the whole width of the box, thereby raising the contents of the box along 70 substantially the entire width thereof.
- Signed by me at Brattleboro, Vermont, this fifteenth day of February, 1915.
